UNITED STATES PATENT OFFICE.

WALTER W. BROWN, OF ERIE, PENNSYLVANIA, ASSIGNOR TO GENERAL ELECTRIC COMPANY, A CORPORATION OF NEW YORK.

CONTROLLING MECHANISM FOR INTERNAL-COMBUSTION ENGINES.

1,132,301.

Specification of Letters Patent   Patented Mar. 16, 1915.

Application filed December 3, 1912. Serial No. 735,659.

To all whom it may concern:

Be it known that I, WALTER W. BROWN, a citizen of the United States, residing at Erie, county of Erie, State of Pennsylvania, have invented certain new and useful Improvements in Controlling Mechanism for Internal-Combustion Engines, of which the following is a specification.

The present invention relates to controlling mechanism for internal combustion engines and especially to engines of the high compression type wherein fuel in a finely divided or atomized state is injected by a blast of air or other means into a highly compressed body of air in the cylinder, the temperature of which is sufficiently high to ignite the fuel.

The application of such engines for various purposes, notably for driving electric generators which in turn supply current to motors on a vehicle carrying said engine, makes it necessary to provide a starting means such as elastic fluid for example and also to provide means for controlling the amount of fuel supplied to the engine to meet the requirements as to load, speed, change in ~~value~~ etc.

The present invention has for its object to provide a controlling mechanism of improved construction for engines and in particular to engines of the character described.

In carrying out my invention I so combine or organize the mechanism that the starting and fuel regulating means are under the control of a single lever or handle. Further said means and the control lever are so arranged that the operator cannot make a mistake in the desired sequence of operation of said means.

For a consideration of what I believe to be novel and my invention, attention is directed to the accompanying description and claims appended thereto.

In the accompanying drawings I have illustrated one of the embodiments of my invention in which—

Figure 1 is a view in end elevation and partial section of an engine fitted with my improved controlling mechanism; Fig. 2 is a detail view showing the eccentrics for driving the cam and pump shafts; Fig. 3 is a detail view of the controlling handle and its connection to the control shaft; Figs. 4 and 5 are sectional detail views showing the means for actuating the fuel valves on op-

posite sides of the engine; Figs. 6 and 7 are similar views of the said means taken at different points; Fig. 8 is a detail sectional view taken on line 8—8 of Fig. 7 showing the lost-motion device associated with the control shaft; Fig. 9 is a view partially in section and plan showing the starting valve mechanism; Fig. 10 is an enlarged sectional view of a part of the fuel pump and its actuating mechanism, and Fig. 11 is a plan view of the same.

Referring to Fig. 1, I have shown an internal combustion engine of the high compression type which may have one, two or more cylinders 15 depending upon the power to be developed. In the present case four cylinders are contemplated. The engine may operate on any desired cycle but the present illustration is directed to a two-cycle engine wherein each cylinder is provided with oppositely moving trunk pistons 16 and 17. These pistons are connected by suitable rods, not illustrated, to the main shaft 18. Each cylinder is provided with two incased exhaust conduits 19, one on each side, and the ports communicating therewith are controlled by the upper piston. The scavenging ports 20 are controlled by the lower piston, said ports receiving air under slight compression from the receiver 21 formed in the base 22 which supports the cylinders.

Each cylinder is provided with two fuel injectors, atomizers or pulverizers 23 and 24 of suitable construction but only one may be used if desired. In the following description reference will be made to means for actuating both pulverizers but it is to be understood that the invention is not so limited unless specifically stated in the claim or claims.

On the right hand side of the engine is a cam shaft 25, Fig. 2, carried by suitable bearings supported by the casing 26, the latter being attached to the engine base 22. On one end of the shaft are two cranks 27, Fig. 1, set 180° apart and these are connected by rods 28 and 29 to eccentric straps surrounding the eccentrics 30 and 31 mounted on one end of the main shaft. The object of the double eccentrics is to prevent as far as possible the cam shaft from being caught on dead center. On the shaft 25 are as many fuel cams 32, Figs. 5 and 7, as there are cylinders.

As is well known a fuel injector, atomizer,

or pulverizer is provided with a needle valve such as 33, Fig. 9, which has to be moved from its seat each time it is desired to inject fuel into the cylinder. To accomplish this a lever 34, Fig. 5, is provided that is made in the form of a bell-crank. One arm of the lever projects under the fuel cam and carries an anti-friction roller for engagement therewith. Under the outer end 5 of this arm and tending at all times to raise it is a coiled compression spring 35. The other arm of the crank rises vertically and is adapted to engage and open the fuel valve 33, Fig. 9, at the proper time. This lever is fulcrumed on an eccentric 36, Fig. 10, which eccentric is mounted on the control shaft 37, the latter extending parallel with the cam shaft as best shown in Figs. 1 to 7, and 10 and 11. This control shaft 20 is rocked or turned in one direction or the other by the operating handle or lever 38, Fig. 3, through suitable means as will appear later. Formed integral with the body of the bell-crank lever 34 or otherwise rigidly secured thereto is a bell-crank lever 39, Figs. 5 and 7, carrying on one of its arms an anti-friction roller arranged to be moved into engagement with the air starting cam 40 carried by the cam shaft 25 in 25 which position it will open the air starting valve at the proper times. I may provide one or more of the engine cylinders with starting means as is desired. For some classes of service one cylinder so provided 30 will be sufficient but in other cases a greater number will be necessary. In the event that only one cylinder is so provided, it will be necessary to bar the main shaft around until the piston or pistons of the 35 starting cylinder is or are just past the dead center. The other arm 41 of the bell-crank lever 39 engages and actuates the air starting valve 42, Fig. 9, through lever means 43. Any suitable means for transmitting motion from this lever to the starting valve may be employed. As shown in Figs. 10 and 11 the control shaft 37 is in 40 position to cause the fuel pump to deliver substantially its maximum amount of fuel 45 to the engine. This shaft is arranged to be turned clockwise to increase and anti-clock-wise to decrease said supply as will appear later. In such an arrangement the control shaft 37 must perform three functions, first move the starting valve into and out of service, second move the fuel valve into and out of service, and third control the supply of fuel. To afford a wide range of adjustment for the pump the movement 45 of the control shaft is preferably greater than is necessary to move the starting and fuel valves into and out of operation. To meet this requirement it is necessary to provide some sort of a lost-motion connection between said shaft and the starting

and fuel levers. Such a connection is shown in Figs. 7 and 8, the latter showing the parts in the air starting position. Rigidly mounted on the control shaft is a member 45 having an internal recess 45^a shown in dotted lines Fig. 7, to receive the projecting end of the lever carrying body 46. The member is also provided with a projection 47 that fits into a slot or recess 47^a formed in the body portion 46. This slot extends 50 over a considerably greater arc than does the projection 47 so that the control shaft can be turned through a greater number of degrees than the said valve actuating levers. The amount of this lost-motion will be determined by the angular movement of the shaft necessary to adjust the pump or pumps from no-load to full-load conditions, and hence will be governed largely by the character of the pump and its regulating mechanism. I may use one or two members 45 as desired depending upon the work to be performed. The principal thing is to have sufficiently large surfaces so that they will 55 not be injured or unduly worn by continued service. The action of these parts on the fuel pump will be described later.

When each cylinder is provided with two pulverizers or injectors the left hand side of the engine will also be provided with a cam shaft 48 which is driven by the eccentrics 30 and 31 through rods 49 and 50, Fig. 1, in the same manner as the right hand cam shaft. It is also provided with a control shaft 51 which, to distinguish it from the 60 first, may be called the secondary control shaft. In order to avoid duplication of parts and to insure exact correspondence in the opening and closing of the fuel valves only one controlling handle is provided and 65 two control shafts are mechanically united. Figs. 4 and 5 show an arrangement for this purpose: Mounted on the end of the primary control shaft 37 is an arm 52 which is connected by the rod 53 with the arm 54 mounted on the secondary control shaft 51. The arrangement of the connection is such that the shafts 37 and 51 move in opposite directions.

Rigidly mounted on the secondary control 70 shaft are as many eccentrics 55, Figs. 4 and 6, as there are engine cylinders and pulverizers or atomizers. Mounted on each eccentric is a bell-crank lever 56 for operating a fuel valve which is similar in construction and operation to that operated by the bell-crank lever 34 of Fig. 5. It is moved in one direction by the fuel cam 56^a mounted on the secondary cam shaft 48 and in the opposite direction by the compression spring 57.

Referring now to the fuel pump and the controlling mechanism therefor shown in Figs. 2, 3, 10 and 11. On the end of cam shaft 25, Fig. 10, is mounted an eccentric 75

60 which is surrounded by an eccentric strap having a projection 61 that is pivotally connected to a projection 62 on the eccentric strap 63, the latter surrounding an eccentric 64 mounted on the control shaft 37. The eccentric 64 serves as an adjustable pivot or fulcrum for the eccentric strap and projection 62 so that as the cam shaft 25 rotates a rocking or oscillating motion is imparted to the eccentric strap and to the lever arm 65, the latter being connected by a link 66 to the upper end of the pump actuator 67. Thus it will be seen that the rotary motion of the cam shaft 25 and eccentric 60 is converted into reciprocating motion of the pump actuator and hence of its plungers as will appear more fully hereinafter. It will be seen that the control shaft 37 and eccentric 64, form a pump governor or regulator for varying the effective delivery of the fuel pump since by changing the angular position of the control shaft 37 and its eccentric the pump actuator will reciprocate in a different region, thereby varying the amount of fuel discharge. The projection 62 and arm 65 constitute in effect a vibratory lever whose fulcrum can be raised or lowered to change the effective pumping stroke. By placing the parts 62 and 65 on the same side of the control shaft instead of on opposite sides I am able to decrease the size of the apparatus as a whole and also to locate the control shaft nearer the cylinders than would otherwise be the case.

The pump is of the displacement type and its output is varied by changing the region of vibration of the plungers without, however, varying the length of their strokes.

Such a pump is disclosed in the application for United States Letters Patent of Hermann Lemp, Serial No. 676,529, filed February 9, 1912. I illustrate this type of pump because it will effectively produce the desired results but other forms of pump can be substituted therefor by making suitable modifications as will be readily understood by those skilled in the art.

68 indicates the guide for the pump actuator and is contained in a casing or reservoir 69, Figs. 2 and 10. As shown eccentric 64 is in position to give substantially the maximum discharge of fuel, and turning it anti-clock-wise from said position will decrease the discharge to the minimum or no load condition. This turning of the eccentric is accomplished by moving the control shaft by the handle 38, Fig. 3.

Referring to Fig. 2, 37 indicates the control shaft and 67 the pump actuator which is connected to and reciprocates the cross-head 70. 71 indicates the pump plungers located in cylinders 72, the latter having ports 73 in their sides which are in communication with the fuel in the reservoir 69.

Each plunger is raised to the upper end of its suction stroke by a coiled compression spring 74 and is depressed by the cross-head 70. The length of stroke of each plunger is the same under all conditions but the region of said stroke is changed. That is to say, the plungers may vibrate so that they extend from a point above the suction ports 73 to the bottom of the cylinders for full load conditions, or they may extend from a point considerably above the suction ports 73 to a point half way down the cylinder in which case only half the amount of fuel will be delivered by the pump. Generally speaking the shorter the distance below the ports 73 that the plunger extends the smaller will be the quantity of fuel delivered. At the base of each cylinder is a spring seated and outwardly opening check valve 75. Communicating with the discharge valve chambers are pipes 76 leading to the fuel pulverizers, such as 23 and 24 of the engine cylinders. One pipe may lead to one pulverizer or to a greater number as desired. In the reservoir 69 is a float 77 for maintaining a constant level of fuel therein. It controls a valve 78 that admits fuel by the pipe 79 from a suitable supply tank, not shown. The lower end of the tank is provided with a drainage conduit 69^a. One or more pumps 95 may be employed, as desired. In Fig. 1 two pumps are shown and mounted on brackets 80. Where two pumps are employed a separate controlling means will be provided for each pump and the two means connected for synchronous operation as for example by the arms 52 and 54 and the rod 53, Figs. 1, 4 and 5.

From the preceding description it will have been noted that the control shaft determines the action of the air starting valve or valves, the fuel valve or valves and the amount of fuel delivered by the pump or pumps by varying the effective stroke thereof. Also it will have been noted that due to the requirements of the situation, certain of the means must have a greater movement than others, said difference in movement being taken care of by the lost-motion device interposed between the control shaft and the starting and fuel valves. In Figs. 2 and 3 is shown the means for actuating the control shaft to attain the desired results. As before stated 38 indicates a handle or lever for rocking the control shaft. It is arranged to move over a segmental plate 81 that may be notched on its edge to receive a retaining latch if desired. The plate is supported by a projection from the shaft casing 82. Extending through the projection is a spindle 125 and mounted on the lower end thereof is a beveled gear 83 which meshes with a similar gear 84 mounted on the control shaft 37. By moving the handle to and fro the engine can be started, stopped and regulated as to 130

speed. As shown the handle has three principal positions indicated by the dotted lines 85, 86 and 87. Line 85 indicates the neutral position in which case the engine is at rest. Moving the handle to the position indicated by dotted line 86 results in cutting out the fuel pulverizers rendering the pumps ineffective as regards the delivery of fuel to the pulverizers and opening the starting valve or valves 42 of which one or more may be provided. As soon as the engine acquires the necessary momentum the handle is quickly swung back across the neutral position 85 which results in cutting out the starting means, and rendering the pumps and fuel valves active. When the position of the handle coincides with dotted line 87 the engine will be working at maximum capacity. A total handle movement of 90° will be found satisfactory. Of this amount 22½° will suffice for the starting operation, and 22½° to give full movement to the injector or pulverizer valves while the governing mechanism of the pump will be set to cause it to deliver one-fourth of its total amount per stroke. From this position to that indicated by line 87 only the pump governing mechanism will be moved resulting in an ever increasing pump discharge. From this it follows that the lost motion between the parts 46 and 47 should, in this embodiment of my invention, be just enough to cause the handle to stop moving the starting and fuel valve levers at quarter load and therefore to move only the pump governing mechanism.

The mode of operation of the apparatus has been fully described hereinbefore but it may be briefly restated as follows: Assuming the engine to be stationary with the pistons in one cylinder in starting position and the control handle 38 at the neutral position, corresponds with dotted line 85, the latter is swung to the right, Fig. 3, which depresses the fuel valve levers 34 to prevent them from actuating the fuel valves, moves the starting valve levers 39 into position to be acted upon by the cams 40 and raises the cross-head 70 of the pump, Fig. 2, so high that the plungers cannot pump because they never move below the suction ports 73. Some one of the starting valves 42 will be opened by its starting cam and air or other elastic fluid under pressure will be admitted to a cylinder whose pistons are close together. The impulse given to the pistons in this manner starts the engine and causes other starting valves to open in proper sequence because they are actuated by the cam shaft and the latter is positively driven by the main shaft of the engine. After the engine has acquired sufficient momentum, the handle 38 is moved across the neutral position thereby moving the fuel valve levers into operative position, as shown

in Fig. 5, and moving the starting valve levers 39 out of operative position. While this is taking place the turning of the eccentric 64, Fig. 10, has so adjusted the fulcrum or center of movement of the arm 65 that it forces the cross-head 70 to have a region of vibration up and down which is low enough to permit the pump plungers to rise above their suction ports on the up stroke due to the springs 74 and to be positively moved to a point below said ports on the down stroke thereby discharging a corresponding amount of fuel. Moving the handle 38 further to the left increases the fuel discharge of the pumps to a maximum. In the broader aspects of my invention it is immaterial what kind of a starting means is employed or the kind of pump or its regulator or the kind of means for actuating the various parts. The main thing is to provide a single means, such as a handle for example, which is so organized or constructed that it can by proper manipulation perform the various operations hereinbefore described.

My improved apparatus has the very great advantage that the operator cannot make mistakes in the sequence of operations necessary. All he has to do is to move one handle forward or back and the engine may be started, stopped, accelerated or retarded to suit the requirements of service. This is a particularly important matter when the engine is employed to drive vehicles for it permits the operator to give the necessary attention to the path ahead and the signals. Having a one handle control for the engine enables the operator to use the other hand to manipulate the electric controlling and braking mechanism.

Another advantage is that for light load conditions the fuel valves are not opened quite so wide as for heavy load conditions, thus preventing the so-called blast air from chilling the contents of the cylinder at the instant of fuel injection. This is due to the fact that the fulcra of the fuel levers are being gradually changed in position by the control shafts 37 and 51 and eccentrics 36 and 55 as the control handle 38 is moved from the neutral point as represented by the dotted line 85 to the next dotted line 88 on the left thereof in Fig. 3.

I have described one form of starting means for the engine but it is evident that other forms of starting means can be employed and controlled by the mechanism described herein.

In accordance with the provisions of the patent statutes, I have described the principle of operation of my invention, together with the apparatus which I now consider to represent the best embodiment thereof; but I desire to have it understood that the apparatus shown is only illustrative, and that

the invention can be carried out by other means.

What I claim as new and desire to secure by Letters Patent of the United States, 5 is:—

1. The combination of an internal combustion engine with a starting means, fuel supply means, and a means organized to actuate the starting means and also to vary 10 the amount of fuel delivered by the supply means to the engine so as to regulate it in accordance with the load.

2. The combination of an internal combustion engine with a starting means therefor, fuel supply means, an actuator, and 15 means responsive to the actuator for putting the starting means into and out of service and for regulating the admission of fuel to the engine so as to vary it in accordance with the load.

3. The combination of an internal combustion engine with a starting means, fuel supply means, a manually controlled actuator, and a means moved by the actuator for regulating the starting means when it is adjusted to one position and for regulating the admission of fuel to the engine in accordance with the load after it has been adjusted to a new position and cutting the 30 starting means out of service.

4. The combination of an internal combustion engine with a starting means, a fuel pump, a regulator for the pump, and a means organized to put the starting means 35 into operation and render the fuel pump inactive through its regulator and also to render said starting means inactive and the fuel pump active.

5. The combination of an internal combustion engine with a starting means, a fuel supply means, an actuator, a means moved by the actuator to control the starting means, a means moved by the actuator to prevent the admission of fuel to the engine 45 when the starting means is in service which includes a lost-motion device, and means moved by the actuator for regulating the amount of fuel supplied to the engine.

6. The combination of an internal combustion engine with a starting means, a fuel pump, a regulator therefor, an actuator, means moved by the actuator for putting the starting means into and out of operation, and means moved by the actuator for 55 adjusting the regulator of the pump after the starting means has been put out of service.

7. The combination of an internal combustion engine having a fuel and a starting valve, a cam shaft, levers moved by the shaft for actuating the valves, a fuel pump, a regulator for the pump, with a controlling means for shifting the levers to bring either set of valves into service and 60 arranged to actuate the pump regulator to

vary the fuel admission whenever the fuel valve levers are in operative relation to the cam shaft.

8. The combination of an internal combustion engine having fuel and starting 70 valves, a cam shaft, actuators for the valves that are responsive to movements of the shaft, a fuel pump, a regulator for the pump, a control shaft for shifting the valve actuators into and out of service, and moving the regulator, and means for moving the shaft.

9. The combination of an internal combustion engine having starting means and a fuel valve, actuators for said means and the 80 valve, a fuel pump, and a cam shaft for actuating said means, fuel valve and pump with means for supporting the actuators, and a device that is common to and moves said supporting means in a predetermined 85 sequence.

10. The combination of an internal combustion engine having starting means and a fuel valve, actuators for said means and the 90 valve, a fuel pump, and a cam shaft for actuating said means, fuel valve and pump with eccentrics that act as pivotal supports for the actuators, and a control shaft for turning the eccentrics.

11. The combination of an internal combustion engine having starting means and a fuel valve, actuators for said means and the 95 valve, a fuel pump, and a cam shaft for actuating said means, fuel valve and pump with means for supporting the actuators, a 100 device for adjusting the position of said supporting means, and a lost-motion connection between said device and the fuel valve actuator to permit it to control the action of the fuel pump.

12. The combination of an internal combustion engine having fuel valves on opposite sides of the cylinder and cam shafts similarly located with means for positively driving said cam shafts, starting means, and control-shafts extending parallel with the cam shafts for moving the fuel valves and starting means into and out of operative position.

13. In combination an internal combustion engine, a starting means therefor, a fuel pump, a valve controlling the admission of fuel to the engine, a regulator for the pump, and a single handle that controls the starting means, fuel valve and action of 115 the pump regulator.

14. The combination of an internal combustion engine, a starting means, fuel admission means, a fuel supply means, and a single means for actuating the starting 125 means and varying the amount of fuel delivered by the supply means to the admission means.

15. The combination of an internal combustion engine, a starting means therefor, a 130

fuel supply means, a control device for actuating the starting means and controlling the fuel supply means, and a handle for moving the device in one direction to cause it to put the starting means into operation and in the opposite direction to control the fuel supply.

16. The combination of an internal combustion engine, a starting means therefor, a pump for supplying fuel to the engine, a hand lever which has a neutral position and other positions at the sides thereof, means actuated by the lever when moved to one side of the neutral position for putting the starting means into operation, and means actuated by the lever when moved to the other side of the neutral position for regulating the amount of fuel discharged by the pump to the engine.
17. The combination of an internal combustion engine, a starting means therefor, a pump for supplying fuel to the engine, a valve for controlling the admission of fuel to the engine, a control handle which has a neutral position and also operative positions on both sides thereof, a means actuated by the handle when moved to one side

of its neutral position for rendering the starting means active and the fuel pump and fuel valve inactive, and means actuated by the handle when moved to the other side of its neutral position for rendering the fuel pump and fuel valve active and the starting means inactive.

18. The combination of an internal combustion engine, a starting means therefor, a pump for supplying fuel to the engine, a control shaft, a handle for moving the shaft which has a neutral position and operative positions on both sides thereof, and means actuated by the shaft so constructed and arranged that when the handle is on one side of its neutral position the starting means is active and the pump inactive, and when the handle is moved to the other side of its neutral position the starting valve is inactive and the pump active.

In witness whereof, I have hereunto set my hand this fifth day of December, 1912.

WALTER W. BROWN.
